R. GARVEY.
FOOT FENDER.
APPLICATION FILED DEC. 5, 1918.

Patented Apr. 22, 1919.

WITNESS:

INVENTOR.

Richard Garvey
BY
Hazard & Miller
ATTORNEY.

UNITED STATES PATENT OFFICE.

RICHARD GARVEY, OF VENICE, CALIFORNIA.

FOOT-FENDER.

1,301,426.

Specification of Letters Patent. Patented Apr. 22, 1919.

Application filed December 5, 1918. Serial No. 265,451.

To all whom it may concern:

Be it known that I, RICHARD GARVEY, a citizen of the United States, residing at Venice, in the county of Los Angeles and 5 State of California, have invented new and useful Improvements in Foot-Fenders, of which the following is a specification.

My invention relates to foot fenders for street cars and the like, and consists of the 10 novel features herein shown, described and claimed.

Figure 1 is a fragmentary perspective showing a foot fender embodying the principles of my invention upon the floor of a 15 car in front of the car seat and in position for use.

Fig. 2 is an end elevation of the foot fender and showing the foot fender out of use in dotted lines.

20 Fig. 3 is a fragmentary enlarged sectional detail through the bottom of the foot fender and showing one of the hinged supports, the view being taken on the line 3—3 of Fig. 4.

Fig. 4 is a fragmentary elevation looking 25 in the direction indicated by the arrow 4 in Fig. 3.

Fig. 5 is a fragmentary sectional detail 30 through the bottom of the foot fender and showing one of the rigid supporting legs, the view being taken on the line 5—5 of Fig. 6.

Fig. 6 is a fragmentary elevation looking in the direction of the arrow 6 in Fig. 5.

Fig. 7 is an enlarged fragmentary perspective of the body of the foot fender.

Referring to the drawings in detail, the foot fender 1 is mounted upon the car floor 2 parallel with and in front of the car seat 3. The main body of the foot fender 1 consists of a plurality of A-shaped frames 4 connected together by a sheet metal bottom 5 and a sheet metal top 6, the bottom 5 and the top 6 being preferably formed of a single sheet bent to fit around the points of the frames 4, and the sheet metal is secured to the frames by rivets 7. The rear side 8 of the fender is open thus providing access to the chamber 9 between the bottom 5 and top 6 and between the frames 4. The rear edge 10 of the top 6 is preferably rolled and wired, and the front edge 11 of the complete fender is rounded to substantially a half circle. The hinged legs 12 are secured to the rear side of the bottom 5. Each leg 12 consists of an attaching plate 13 secured to the floor 2 a post 14 extending upwardly from

the plate 13, bearing members 15 and 16 extending upwardly from the posts 14, an attaching plate 17 secured against the lower face of the bottom 5, a bearing member 18 60 extending from the attaching plate 17 between the bearing members 15 and 16, and a bolt or hinge pin 19 inserted through the bearing members 16, 18 and 15. The attaching plate 13 may be secured to the floor by 65 screws 20 and the attaching plate 17 may be secured to the bottom 5 by rivets 21.

The rigid supporting legs 22 have attaching plates 23 formed integral with their upper ends and secured to the front part of 70 the bottom 5 by rivets 24.

An ordinary street car is 90 inches wide inside. The side seats 3 are 17 inches wide and 20 inches high. The distance between the side seats 3 is 56 inches. My foot fender 75 is preferably 10 inches wide from the front edge 11 to the rolled rear edge 10, and the fender is set to leave a space 25 between the rear side of the fender and the front face of the seat 3 which is 8 inches wide. This 80 will leave a space between the front edges 11 of the two fenders 20 inches wide.

The passengers will stand and walk upon the floor 2 in this 20 inch space between the two fenders. The passengers who are to occupy the seats 3 will step over the fenders 1, and when sitting upon the seats 3 their feet will rest with their heels upon the floor 2 and the toes extending through the opening 8 into the chamber 9. Then the passengers 85 standing in the center of the car between the fenders cannot walk upon the feet of the passengers occupying the seats or stumble over them, and when the passengers are walking up and down the car in the 20 inch 90 space they cannot be tripped by the feet of the passengers occupying the seats. The passengers standing upon the floor or in the center of the car may stand with their toes 95 extending under the rounded edges 11 of 100 the fenders, and in passing over the fenders to the seats they may step upon the top 6.

When it is desired to sweep the floor 2 of the car, the space 25 may first be cleaned and then the front edge 11 of the fender may be 105 turned upwardly until the rolled edge 10 rests upon the floor, as shown in dotted lines in Fig. 2, and then the spaces which were under the fender may be cleaned.

When the foot fender is in its normal position for use, as in Figs. 1 and 2, the bottom 5 is at a comfortable incline, so that the oc-

cupant of the side seat 3 will rest his heels upon the floor 2 with his toes extending through the opening 8 on to the bottom 5.

Various changes may be made without departing from the spirit of my invention as claimed.

I claim:

- 10 1. In a foot fender, vertical frames, a sheet metal body mounted upon the frames and forming a chamber and an opening to the rear side of the chamber, legs for hingedly connecting the rear side of the body to the floor of a car, and rigid legs for supporting the front part of the body.

Copies of this patent may be obtained for five cents each, by addressing the "Commissioner of Patents, Washington, D. C."

2. A foot fender for street cars or the like 15 comprising A-shaped frames, a sheet metal body fitting upon the frames and extending around the points of the frames to form a rounded edge at one side and an open chamber at the other side, legs for hingedly connecting the rear part of the sheet metal body to the floor of a street car, and legs for supporting the front part of the body above the floor of a street car.

20 In testimony whereof I have signed my name to this specification.

RICHARD GARVEY.
